UNITED STATES PATENT OFFICE.

ROBERT COCHRAN DICKSON, OF MEDAN DELI, SUMATRA.

METHOD AND MEANS FOR RAISING WATER OR OTHER LIQUID BY COMPRESSED AIR.

Application filed September 8, 1920, Serial No. 408,915.

To all whom it may concern:

Be it known that I, ROBERT COCHRAN DICKSON, mechanical engineer, A. M. T. M. E., a subject of the King of Great Britain, 5 residing at 10 Poloniaweg, Medan Deli, Sumatra, have invented certain new and useful Methods and Means for Raising Water or Other Liquid by Compressed Air; and I do hereby declare the following to be 10 a full, clear, and exact description of the invention, such as will enable others skilled in the art to which it appertains to make and use the same.

This invention relates to a method of, and 15 automatically acting means for, pumping or raising water or other liquid by compressed air.

The method according to this invention of raising liquid (practically in a continuous 20 stream) by means of compressed air consists, in employing a single submersible air-tight tank divided into two air-tight compartments—or if desired two separate juxtaposed air-tight tanks or containers herein- 25 after referred to as compartments—the two compartments being preferably identical and each of said compartments being provided with an admission port, an air exhaust port for the compressed air, and admission 30 and discharge valves for the liquid to be raised, and in discharging the liquid from the said compartments alternately by utilizing the resultant of the varying efforts of two weights (one in each of said compartments) and two float weights (one in each 35 compartment) each weight and float weight in each said compartment respectively being subjected to the alternate rise and fall of liquid in the said compartment to reverse 40 the supply of compressed air from one compartment to the other and by making the opening of the exhaust port for the compressed air in each compartment successively follow immediately after the closing of 45 the corresponding admission port for the compressed air in that compartment.

One construction of apparatus adapted to raise liquid (practically in a continuous 50 stream) in accordance with the method set forth above is illustrated in the accompanying drawing, a single submersible air-tight tank divided into two air-tight compartments being shown:—

Fig. 1 being a plan of the tank.

Fig. 2 a vertical section on the line X—X of Fig. 1.

Fig. 3 being a vertical cross-sectional view on the line Y—Y, Fig. 2—looking in the direction of the arrows thereon.

Fig. 4 is a fragmentary sectional view 60 showing in detail the trigger mechanism.

A A¹ are the two separate compartments aforesaid provided with a cover B; water inlet valves C C¹; water discharge valves D D¹; air inlet valves E E¹; and air exhaust 65 valves J J¹.

The air inlet valves E E¹ are provided with eyes above and below the valve seats. The eyes above the valve seats being connected to the extremities of a rocking lever 70 F which moves about the fulcrum G, see Fig. 3.

The eyes below the inlet air valve seats are connected at H² by the rods E² to independent levers H H¹ to the extremities of which latter are suspended weights I I¹ which may be open-topped pots I I¹ which when filled with water act as weights. The weight I is preferably heavier than the weight I¹. 75

The exhaust valves J J¹ are provided with eyes below the valve seats connected by the rods J² to independent levers K K¹ pivoted at W and having float-weights L L¹ suspended at their extremities. These float- 80 weights L L¹ act in the double capacity of floats when the compartments A A¹ are filled with water and weights when the water is discharged or partly discharged from said compartments; the axles Z Z¹ acting as fulcrums of the levers H H¹ are fixed to the levers at one end and have triggers T T¹ fixed at the other ends which engage with catches on the ends of the levers K K¹. 85

On the upper side of the cover B are (a) a hollow chamber M extending over both air inlet valves E E¹ having an opening M¹ for connecting to an air supply pipe and (b) a hollow chamber O which extends over both outlets from the water discharge valves D D¹, and provided with an opening P for connecting to a water discharge pipe. 90

The air exhaust valves J J¹ may be screwed exteriorly to suit independent air exhaust pipes or otherwise. 100

The action is as follows:—

The tank, i. e., the entire contrivance, is submerged in water.

Both compartments fill through the water inlet valves C C¹. The floats L L¹ rise with 110 the water to the top of the compartments A A¹. The weight I being slightly heavier

than the weight I^1 the air inlet valve E remains closed. Compressed air is admitted to the conduit M and as it fills the compartment A^1 through the air inlet valve E^1 it expels 5 the water through the discharge valve D^1 . As the level of the water in the compartment A^1 is reduced the float L^1 becomes a weight but remains at the top of the compartment held in this position by the trigger T^1 .

10 The weight I^1 becomes heavier and heavier as the water recedes until it overcomes the air pressure on the air inlet valve E (in the other compartment) and opens it closing the air inlet valve E^1 simultaneously.

15 The movement of the lever H^1 releases the trigger T^1 and allows the float weight L^1 to drop and open the exhaust valve J^1 . The opening of the air inlet valve E raises the lever H connected with it and engages the trigger T thus preventing the float weight L from dropping.

20 When the pressure inside the chamber A^1 is released by the opening of the exhaust valve J^1 this chamber fills with water through the water inlet valve C^1 .

25 The action described above takes place alternately in the chambers A , A^1 , as long as air pressure is supplied.

30 V and V^1 are dash-pots to bring the descending float weights to rest gently.

35 The trigger action above referred to is—for example—obtained by providing the lever K K^1 with fixed abutments S S^1 and the triggers T T^1 with sears or abutments R R^1 which latter are adapted to engage and hold the abutments S S^1 and thereby lock the levers K K^1 in turn until the triggers T T^1 are rocked as aforesaid and so release the 40 levers K K^1 in turn.

45 What I claim is:—

1. Apparatus for raising liquid—practically in a continuous stream—by means of compressed air; comprising two submersible air-tight contiguous compartments each provided with inlet and discharge valves for the liquid to be raised and admission and exhaust valves for the compressed air, means in each compartment actuated by the fall of 50 liquid in one compartment to close the corresponding air admission valve for that compartment and open the air admission valve for the other compartment, means in each compartment for opening the corresponding 55 air exhaust valve and adapted to be set in operative position by the previous rise of liquid in the same compartment and means actuated upon the opening movement of the air admission valve for positively locking the 60 said air exhaust valve and opening means

in the operative position and for unlocking the same upon the closing movement of said air admission valve substantially as set forth.

2. In apparatus according to claim 2 an 65 overload upon one of the admission valves for the compressed air with respect to the load on the other air admission valve whereby the raising of the liquid is automatically started upon the admission of compressed 70 air substantially as described.

3. An apparatus for raising liquid by means of compressed air, comprising two submersible air-tight contiguous compartments provided with inlet and discharge 75 valves for the liquid to be raised, and admission and exhaust valves for the compressed air and means for controlling the operation of said compressed air valves so as to cause the liquid to be raised alternately from 80 said compartments, said means acting upon movement of the weight mechanism in opposite directions to open and close the compressed air admission valves of the compartments, connections between the compressed 85 air admission valves constructed to cause one of said valves to be opened when the other valve is closed, and means for locking the air exhaust valve of each of the compartments in closed position, when the compressed air admission valve of the compartment is open.

4. An apparatus for raising liquid by compressed air, comprising a chamber provided with inlet and discharging valves for the liquid being raised and admission and exhaust valves for the compressed air, mechanism for closing the compressed air admission valve, means for closing the air exhaust valve and means controlled by said 90 mechanism for locking the air exhaust valve in closed position when the compressed air admission valve is in open position.

5. An apparatus for raising liquid by means of compressed air, comprising a chamber provided with inlet and discharge valves for the liquid to be raised, and admission and exhaust valves for the compressed air, mechanism for opening and closing the compressed air admission valve, means for closing the air exhaust valve and trigger mechanism associated with said first-mentioned mechanism and said means, said trigger mechanism being constructed to lock the air exhaust valve in closed position when the air admission valve is open and to unlock the air exhaust valve when the air admission valve is closed.

ROBERT COCHRAN DICKSON.
